UNITED STATES PATENT OFFICE

2,435,666

MONEY-CHANGER

Gee Jan Wong, Santa Barbara, Calif.

Application October 7, 1943, Serial No. 505,362

6 Claims. (Cl. 133—5)

1

My invention relates to the handling and disposition of money on buses, street cars and the like, and includes among its objects and advantages the provision of an improved money-changer wherein novel means are incorporated for arranging coins of different denominations in an orderly manner and selectively removing the respective coins for change making purposes, in which the money-changer is in the nature of a unit which may be carried on the person, and in which novel means are provided for protectively housing the unit when in the vehicle and locking the coin actuating keys against unauthorized tampering.

In the accompanying drawings:

Figure 1 is a face view of the change maker and its housing.

Figure 2 is a top view.

Figure 3 is a sectional view along the line 3—3 of Figure 1.

Figure 4 is a sectional view along the line 4—4 of Figure 1.

Figure 5 is a sectional view along the line 5—5 of Figure 1.

Figure 6 is a sectional view along the line 6—6 of Figure 4.

Figure 7 is an end view of the money-changer in an opened position, with its protective housing illustrated in section.

Figure 8 is a fragmentary perspective view of one of the coin pushers.

Figure 9 is a sectional detail view of a latch.

Figure 10 is a sectional view of the structure of Figure 9 but rotated 90 degrees in two directions, and

Figure 11 is a sectional view along the line 11—11 of Figure 4.

In the embodiment of the invention selected for illustration, the money-changer 10 comprises a floor 12 having a cent tube 14, a 5-cent tube 16, a 10-cent tube 18, a 25-cent tube 20 and a 50-cent tube 22 mounted thereon. These tubes are arranged in a straight line, as when viewing Figure 3, and the tubes are arranged vertically on the floor 12. All the tubes are provided with longitudinal slots 24 to indicate the supply of coins therein.

In Figure 5, coin discharging openings 26 are provided in the floor 12. These openings are located in a straight line slightly to one side of the line of coins 28 when stacked in the respective tubes. At the lower ends of the tubes 14 through 22 are located coin pushers 30 for removing one coin at a time from their respective tubes. All the pushers 30 are identical, with the exception

of size, so that the description of one will apply to all.

In Figure 8 the pusher 30 lies in a recess 32 in the floor 12. The pusher includes a curved finger 34 having an inside diameter corresponding to the diameter of the coin for which it is designed. The finger curves throughout an arc exceeding 180 degrees, and the lowermost coin in the tube associated with the finger drops within the finger 34 and lies on the bottom face 36 of the recess 32. A coin supporting wing 38 is provided on the finger 34 to constitute a support for the coin stack above the lowermost coin when the pusher 30 is pivoted from its normal position of Figure 8 to a position concentrically of the coin discharging opening 26 to drop the coin through the opening.

The pusher 30 is pivotally connected at 40 with the floor 12 and includes a segmental gear 42 meshing with a segmental gear 44 pivotally connected at 46 with the floor 12. A bar or lever 48 is pivotally mounted on a shaft 50 and includes a finger 52 extending through an opening 54 in the segmental gear 44 so that rotary motion may be imparted to this gear through oscillatory motion of the bar 48. A spring 56 is coiled on the shaft 50 and has one end abutting the bar 48 and its other end engaging the floor 12 to yieldingly hold the bar in the position illustrated. Downward pivotal movement of the bar 48 rotates the segmental gear 44 in a clockwise direction and the segmental gear 42 in a counterclockwise direction, as when viewing Figure 8, to bring the pusher 30 into coin discharging alignment with the discharge opening 26.

Figure 3 illustrates the bars 48 as being provided with buttons 58 appropriately marked at 60 to designate the denominations of the respective coins actuated thereby. The shafts 50 are supported in brackets 62 mounted on the floor 12. Slots 64 are provided in the wall 66 of the unit 10 for accommodating the bars 48. Slots 66 are also provided in the wall 66 in alignment with the slots 24 to expose the coin supply to view.

The money-changer or unit 10 includes a wall section 70 and a wall section 72 hingedly connected therewith at 74. The floor 12 is carried by the wall section 72. The tubes 14 through 22 each comprises a section 76 carried by the wall section 72 and a section 78 carried by the wall section 70. A spring pressed latch 80 is pivoted on the wall section 70 for detachably connecting the two sections in the manner of Figure 4, but the section 72 may be pivoted downwardly to facilitate placement of coins in the

sections 76 and then swinging the wall section 72 up to the position of Figure 4.

A case of protective housing 82 is provided for the money-changer 10. This housing is provided with horizontal channels 84 running into vertical channels 86 closed at their bottom ends. Pivots 88 are attached to the wall section 72 and are receivable in the channels 84 and 86. Normally the pivots 88 lie at the bottom ends of the vertical channels 86, and the money-changer 10 is latched to the housing through the medium of bars 90. The two bars 90 are slidably mounted in a guide 92, see Figure 11, and are biased outwardly of the guide by springs 94. Lugs 96 are attached to the housing 82 and are slotted at 98 providing sockets for the reception of the outer ends of the bars 90. Each bar includes an up-standing arm 100 having a wing 102 accessible from a position forwardly of the money-changer. The wings 102 are closely spaced so that the two wings may be grasped between the thumb and the index finger of the hand and shifted toward each other for retracting the bars 90 out of holding engagement with the lugs 96.

Means is provided for locking the bars 90 in their projected positions to secure the money-changer 10 to the housing 82, the latter being preferably fixedly mounted in the vehicle. This means comprises a latch bar 104 slidably mounted in a lock housing 106 and having its lower end slidably through an opening 108 in the lock housing. The latter is provided with a key receiving opening 110, and the bar 104 is provided with a key receiving notch 112. A light spring 114 is attached to the bar 104 and engages one wall of the lock housing 106. Thus the bar 104 may be moved downwardly through the medium of a key inserted in the lock housing to position the lower end of the bar 104 between the two bars 90 for latching the latter against unauthorized retraction. Figure 11 illustrates the bar 104 in its unlatching position, at which time the bars 90 may be retracted.

Means is also provided for latching the bars 48 against unauthorized actuation. A bar 116 is slidably mounted in the wall section 72 and is provided with depending arms 118 having lugs 120 engageable underneath the bars 48 when the bar 116 is shifted to the right, as when viewing Figure 6, against the tension of a spring 122.

Figures 9 and 10 illustrate the bar 116 as being provided with an ear 124 extending through an opening 126 in the wall 66. An ear 128 is fixed to the wall 66 a short distance from the ear 124 to facilitate a thumb and finger grasp on the two ears for shifting the bar 116 and bring the lugs 120 underneath the bars 48.

A latch pin 130 is slidably mounted in a bracket 132 attached to one of the wall faces 134 between the tube sections 76. A compression spring 136 is interposed between the end 138 of the bracket and a flange 140 fixed to the pin 130 to urge the latter against the bar 116. An opening 142 is provided in the bar 116 for the reception of the pin 130 when the bar 116 has been shifted sufficiently far to bring the lugs 20 underneath the bars 48. The bar 116 may be unlatched only through actuation of a lever 144 pivotally connected at 146 with the pin 130 and fulcrumed at 148 in a plate 150 attached to the bracket 132. Since the pin 130 and the lever 144 are located on the inner side of the wall 66, access can be had to the lever 144 only through separation of the wall sections 70 and 72. Such separation of the wall sections may be attained only through re-

lease of the latch bars 90, which are key controlled.

The money-changer 10 is provided with two loops 152 for connection with shoulder straps in cases where the money-changer is carried on the person. The housing 82 carries a money receiving tray 154 located underneath the coin discharging openings 26.

The wall sections 70 and 72 are recessed to provide slots 156 through which coins may be dropped in the chutes 14 through 22.

Without further elaboration, the foregoing will so fully explain my invention, that others may, by applying current knowledge, readily adapt the same for use under various conditions of service.

I claim:

1. In a money changer comprising a protective housing, a sectional money changing unit in the housing, forming coin tubes, means for removing coins one at a time from the coin tubes including pivoted bars and pushers, the combination of latch means manually accessible from a position exteriorly of one of the sections for holding the bars against actuation, and releasing means in said section for the latch accessible only from a position within said section.

2. A money-changer, comprising a protective housing, a money changing unit removably and pivotally mounted in said housing, latching means carried by said unit adapted to co-act with keepers on said protective housing to retain said unit within said housing, and key controlled means for retaining said latching means in said keepers.

3. A money-changer, comprising a protective housing, horizontal channels on the ends of said housing, vertical channels at right angles thereto and communicating therewith, a money changing unit having pivots formed on the end thereof to co-act with said channels and pivotally and removably mount said unit in said housing, latching means carried by said unit adapted to co-act with keepers on said protective housing to lock said unit within said housing, and key controlled means for locking said latching means in said keepers.

4. The invention as described in claim 3, wherein manually operated arms are provided on the exterior of said unit to operate said latching means.

5. In a money changer, the combination, which comprises, a housing having rear and end walls and a base, said end walls carrying sockets and having channels indented therein and said base carrying a coin receiving tray, a plurality of coin tubes having coin ejecting levers associated therewith and pins extending at the ends positioned in the channels in the ends of the housing providing removable mounting means of the coin tubes in the housing, bars slidably mounted on the coin tubes positioned to extend into the sockets of the ends of the housing to lock the coin tubes in the housing, resilient means urging the bars into the said sockets, and means locking the bars in the sockets.

6. In a money changer, the combination, which comprises, a housing having rear and end walls and a base, said end walls carrying sockets and having channels indented therein and said base carrying a coin receiving tray, a plurality of coin tubes having coin ejecting levers associated therewith and having pins extending at the ends positioned in the channels in the ends of the housing providing removable mounting means of the coin tubes in the housing, bars slidably mounted on the coin tubes positioned to extend

into the sockets of the ends of the housing to lock the coin tubes in the housing, a key actuated lock bolt securing the bars in the sockets, and thumb and finger grips for withdrawing the bars to release the coin tubes from the housing.
